UNITED STATES PATENT OFFICE.

CHARLES H. LANDENBERGER, OF PHILADELPHIA, ASSIGNOR TO HIMSELF, MARTIN LANDENBERGER, AND MARTIN LANDENBERGER, JR., OF SAME PLACE, AND CHARLES WEILER, OF LANDENBERG, PENNSYLVANIA.

DESIGN FOR SHAWL.

Specification forming part of Design No. 7,532, dated July 7, 1874; application filed June 27, 1874.
[Term of Patent 3½ years.]

CASE B.

To all whom it may concern:

Be it known that I, CHARLES H. LANDENBERGER, of Philadelphia, Pennsylvania, have produced or invented a Design for a Shawl, of which the following is a specification:

The nature of my design for a shawl is clearly represented by the figure in the accompanying drawing.

The groundwork of the shawl is uniform throughout, both for the body A and for the borders B, C, D, and E; but the body is ornamented by parallel stripes *a*, which end abruptly at the borders, a strong contrast between the body and the borders of the shawl being thus presented.

Irrespective of the shades or colors em-

ployed, or of the minor ornamentation of the stripes or groundwork, I claim—

The design for a shawl having a uniform groundwork throughout, and a body, A, ornamented by parallel stripes *a*, which terminate abruptly at the borders B, C, D, and E, all as described, and as represented in and by the accompanying drawing.

In testimony whereof I have signed my name to this specification in the presence of two subscribing witnesses.

CHARLES H. LANDENBERGER.
